J. B. EASTON.

WINDOW VENTILATOR.

APPLICATION FILED MAY 23, 1916.

1,238,651.

Patented Aug. 28, 1917.

UNITED STATES PATENT OFFICE.

JAMES B. EASTON, OF NEW YORK, N. Y.

WINDOW-VENTILATOR.

1,238,651

Specification of Letters Patent. Patented Aug. 28, 1917.

Application filed May 23, 1916. Serial No. 99349.

To all whom it may concern:

Be it known that I, JAMES B. EASTON, a citizen of the United States, residing at New York city, in the county of New York, State of New York, have invented certain new and useful Improvements in Window-Ventilators; and I do hereby declare the following to be a full, clear, and exact description of the invention, such as will enable others skilled in the art to which it appertains to make and use the same.

This invention relates to improvements in ventilators, and has special reference to that type of ventilator which is used in connection with a window having a vertically sliding lower sash.

An important object of the invention is to provide an improved form of window ventilator wherein the opening for the admission of air will be varied in size by the intensity of the draft passing through such ventilator, the variation in the draft pressure being caused principally by the variation of wind pressure outside of the building wherein the ventilator is used.

Another important object of the invention is the provision of an improved ventilator of this type wherein improved means will be utilized for regulating the maximum opening in such a ventilator so that the latter may be partially closed during excessively cold and still weather.

With the above and other objects in view, as will be hereinafter apparent the invention consists in general of certain novel details of construction and combinations of parts hereinafter fully described, illustrated in the accompanying drawings and specifically claimed.

In the accompanying drawings, like characters, of reference indicate like parts in the several views, and:—

Figure 1 is a plan view of such a ventilator showing its relationship to the coöperating parts of the window frame and sash;

Fig. 2 is an outside elevation of a portion of a window frame and sash showing the ventilator in position;

Fig. 3 is a section on the line 3—3 of Fig. 1 and showing the ventilator closed in dotted lines;

Fig. 4 is an enlarged detail section showing the regulator or stop used to limit the extent of opening of the ventilator.

In the present embodiment of the invention the same has been shown as applied to a window whereof the sides of the frame are shown at 10, the sill at 11, the stool at 12 and a sliding sash at 13.

The invention itself consists of a casing 60 having an open front or outer side formed partly by the vertically spaced longitudinal members 14 and partly by the end members 15. These end members have their upper outer corners rabbeted as at 16 to receive 65 the lower part of the top member 14 and have their upper edges connected by a top member 17. The inner and under edges of the members 15 are inclined to each other at an obtuse angle, the under edge being inclined upwardly from front, to rear as can be clearly seen by reference to Fig. 3. The inner or rear edge of the top member 17 has depending beneath it a guard apron 18 having its lower edge transversely arcuate as at 75 19 and secured to the end members 15 in spaced alignment below the apron 18 is a supporting plate or rib 20. The bottom is closed in by a closure 21 and the inner side by a closure 22 which extends upward to the 80 top edges of the ends 15 and between whose upper edge and the inner or rear edge of the top 17 is secured a wire screen 23 to keep out insects and the like.

Journalized in the ends 15 just below the 85 top 17 and close to the upper member 14 is a valve plate 24 which normally hangs down as shown in full lines in Fig. 3. This valve plate has secured to its inner face an arcuate guard plate 25 which moves beneath 90 the arcuate lower edge of the apron 18, the curvature of said edge and guard plate being concentric to the journal axis. The true bottom of the casing consists of a transversely arcuate metal plate 26 the center of 95 curvature of which lies outside and below the horizontal plane of the journal axis so that as the free edge of the valve plate 24 swings inward, under the influence of wind pressure on its outer face, this edge will 100 approach the bottom and thus reduce the size of the opening between said edge and said bottom. Thus the greater the exterior pressure the less the opening and in consequence the air admitted to the room will 105 at no time be in such excess as to chill the room or its occupants.

To the end that, under such conditions as a violent wind, the opening may be entirely closed the upper edge of the bottom 110

26 is so positioned on the support or rib 20 that the free edge of the valve plate 24 will almost touch such upper edge when swung into proximity thereto. In order to prevent opening of the space if the valve plate 24 swings inwardly of this bottom there is provided a supplemental bottom 27 arranged rearwardly of the bottom 26 and transversely curved concentric to the journal axis.

10 At times, as when the weather is cold and still, it is desirable to partly close the valve and in order to effect this an adjusting screw 28 is threaded through the top 17, a plate 29 being used to prevent wear. This screw 15 has its lower end positioned adjacent the outer face of the valve plate and is arranged to engage an elastic buffer 30 carried by a spring member or arm 31 fixed to the outer face of the valve plate. By this means the 20 valve may be partly closed by screwing the adjusting screw downward and yet left free to close further under wind pressure.

It is obvious that the valve may be wholly closed by sufficient adjustment of the screw 25 downward and that the buffer will prevent unpleasant noises.

To hold the ventilator removably in place, fastening means typified by the beads 32 30 may be employed and the ventilator may be equipped with weather strips 33.

There has thus been provided a simple and efficient device of the kind described and for the purpose specified.

It is obvious that many minor changes 35 may be made in the form and construction of the invention without departing from the material principles thereof. It is not therefore desired to confine the invention to the exact form herein shown and described but 40 it is wished to include all such as properly come within the scope claimed.

Having thus described the invention, what is claimed as new, is:—

1. In a window ventilator, the combination with a casing having an inner wall 45 and a top member spaced outwardly from the top of the inner wall, a guard apron depending from the inner edge of the top member, valve plate journaled beneath the top, an arcuate guard plate carried by the 50 valve plate, said guard plate being concentric to the journals of the valve plate having its free portion extending beneath the lower edge of the apron in close proximity thereto, said casing having a bottom portion 55 located beneath the path of the free edge of the valve plate and curved eccentrically of the valve plate journals to cause the free edge of the valve plate to approach the bottom as the valve swings inwardly. 60

2. A window ventilator comprising a rectangular frame, end walls projecting from one face of said frame, a bottom wall and a front wall connecting the end walls of the frame, a top wall terminating short of 65 the upper edge of the front wall, a guard apron depending from said top wall, a swinging valve plate depending from said top wall and normally lying in the same plane as the guard apron, a guide member 70 carried by said swinging valve plate and adapted to engage the lower edge of the guard apron, and means projecting through the top wall and engaging the swinging valve plate for restricting the passage open. 75

In testimony whereof, I affix my signature, in the presence of two witnesses.

JAMES B. EASTON.
